WINDOW CONSTRUCTION

Roy T. Axe, Syracuse, N. Y., assignor to The
O. M. Edwards Company, Inc., Syracuse, N. Y.,
a corporation of New York

Application October 12, 1938, Serial No. 234,660

4 Claims. (Cl. 189—72)

This invention relates to window constructions, and has for its object a sash which may be opened and closed or raised and lowered, and has easily-accessible and operable means self-contained therewith for adjusting the sash to the variations in the widths of the window openings or window frames of a vehicle body and to misalignments of the posts out of the vertical at the sides of the window openings or between the window openings, so that standard sashes may be adjusted to window openings and adjustments readily made when installed for the variations in width and for misalignments, in order that the sash may raise and lower easily under all conditions and at the same time be anti-rattling and weather tight.

The window openings of vehicle bodies as buses, railway cars, and the like, although intended to be uniform, vary in width, and also the posts at the sides of the window openings or between the window openings incline out of the vertical. In some instances, these openings are somewhat key-stone in shape, and in other instances, somewhat rhomboid shape. In others, variations or combinations of these shapes. With both perfectly rectangular window openings and the irregular openings, widthwise adjustments are necessary.

The sash equipment is furnished by the supplier to the car builder and must be adaptable to the variations and misalignments of the window openings, in order that the sashes will raise and lower easily and uniformly under all conditions at the same time be weather tight and also be cushioned against the weavings of the car body.

The general object of the invention is a sash structure that will conform to all these conditions.

The invention consists in the novel features and in the combinations and constructions hereinafter set forth and claimed.

In describing this invention, reference is had to the accompanying drawings in which like characters designate corresponding parts in all the views.

Figure 1 is a fragmentary elevation of a window structure embodying this invention.

Figure 2 is a sectional view on line 2—2, Figure 1.

Figures 3 and 4 are enlarged sectional views on lines 3—3 and 4—4, Figure 2.

Figure 5 is a sectional view on line 5—5, Figure 3.

Figure 6 is a view similar to Figure 3 of a slightly modified form of the invention.

1 designates the car body formed with window openings confined by the inner and outer sheetings 2, 3 of the car body, and sill 4, the vertical 5 portions of the sheeting along the sides of the window opening having inwardly extending flanges 5 constituting what are usually called posts, these posts also including additional sheeting 6 on the inner side of the car body. 10

In the window structure here shown, a lower stationary sash 7 and an upper slideable sash 8 are shown, the upper sash 8 closing down on the top rail 9 of the lower sash, this top rail serving as a sill for the upper sash. The upper sash 15 slides upwardly from closed position.

The invention comprises means self-contained with the slideable sash and coacting with the sash guides for adjusting the sash to variations in the widthwise spacing of the guides and to misalignments of the guides and to take up or absorb weaving of the superstructure of the car or bus body without straining the sash frame. More specifically, the invention comprises a sash having its stiles slideable in the window opening and slidably interfitting with guide members mounted in the window opening or the window frame, one of the slidably engaging parts being formed with a channel and the other with a tongue or rib extending into the channel, and elements, as 30 shoes, carried by the sash or the stiles thereof and coacting with the guide members at spaced apart points, these shoes or elements being adjustable independently of each other to cause the sash to coact with the guide members uniformly throughout the movement of the sash irrespective of misalignments in the window openings and the guides and variations in the width of the openings. It further includes adjusting means carried by the stiles and operable 35 from the inner edges of the stiles in a direction edgewise of the sash. 40

The invention further comprehends a non-metallic resilient cushion, U-shaped in general form, carried by the sash or the stiles thereof 45 and interposed between the stiles and the sash guides and having openings in the bottom of the U formation in which said elements or shoes are located.

The sash 8 is shown as formed of metal, usually extruded metal, to have a channel 10 for receiving a mounting 11 for the glass pane 12 and also with a channel 13 located in the plane of the sash, and also with portions, as 14, offset from 50 55

the plane of the sash for coacting with the guide member on the post 5.

In the embodiment of my invention shown in Figures 1 to 5, the guide members are shown 5 as ribs 15 which extend into channels 16 formed in the offset portions 14, each channel 16 being provided with a liner 16^a of non-metallic flexible cushioning material, U-shaped in general form in cross section.

10 The means for adjusting the sash for variations in width and for misalignments of the guide members or ribs 15 comprises elements coacting with the edge of each rib 15 and means for adjusting the elements in a direction edgewise of

15 the sash, this consisting of individual parts spaced along the stile of the sash and carried by the offset portion 14 and operable from the inner edge of said portion 14 in a direction edgewise of the sash.

20 In the illustrated embodiment of my invention, the elements coacting with the guide rib 15 are blocks or shoes 17 preferably of a non-metallic material and located in openings 18 in the bottom of the U-shaped liner 16^a, and the adjusting

25 members consist of screws 19 threading through the inner edge of the offset portion 14 in a direction edge wise of the sash or through the bottom of the channel 16. The screws preferably thrust through springs 20 against the blocks or 30 shoes 17. The heads of the screws are exposed on the inner edge of the portion 14 of the stile of the sash.

In the illustrated embodiment of the invention, an additional strip 21 is secured to the bottom 35 of the offset portion 14 of the stile, as by screws 22. The adjusting screws 19 thread through the strips. The outer ends or heads of screws 19 are suitably formed to receive a tool, they being here shown as formed with a socket 40 23 for receiving a wrench. The upper and lower ends of the channel 16 are closed by cover strips 16^b which hold the liner from endwise displacement.

Each rib 15 projects from a suitable base plate 45 24 which is secured to the post structure by interlocking one edge or lip at 27 under an overhanging flange 28 on a strip 29 secured to the post structure, as by screws 30, and by screws 31 extending through the base plate and into the 50 post structure after the edge or lip 27 has been interlocked under the flange 28. A rack 32 is secured to the base plate and extends into the channel 13 of the sash, this rack coacting with the bolt 33 of a sash holder located within the 55 bottom rail of the sash 8 and operable by a lever 34 on the outside of the rail.

The lower stationary sash 7 is similar in construction to the upper sash 8 with the exception that it being stationary, no provision is made for 60 raising and lowering it or for misalignments and widthwise adjustment. The sash 8 is provided with a suitable weather stripping 35 along its top rail for rendering it weather tight when the sash is closed.

65 In Figure 6, the guide 40 is shown as channel-shaped for receiving the stile 41 of the sash, as the cushioning strip 42 embraces the stile 41 and is carried thereby. The shoes 43 are located in openings 44 in the bottom of the U formation of 70 the cushioning strips 42. The shoes 43 are individually adjustable by screws 45 threading into the offset portion 46 of the sash or stile, in a direction edgewise of the sash. They thrust against the shoe through springs 47.

75 In operation, the sash and guide equipment is

furnished by the manufacturer, to the car builder and the sash is accurately rectangular. The guide equipment is also furnished by the sash manufacturer. The car builder first secures the strip 5 29 to the post structure and then applies the sash guide with a sash therein by inserting the base flange of the sash guide under the flange 28 of strip 29, and then applies the screws 31. He then manipulates the adjusting screws 23 for the widthwise adjustment and for adjustment as to 10 misalignments, so that although a window opening may be a trifle key-stone or rhomboid shape, or variations of these shapes, the adjustment may be made by means of screws 19, so that the sash slides vertically under all conditions and 15 with uniform pressure and without looseness.

Owing to this adjustment and to the springs 19, the sash adapts itself to misalignments and raises and lowers or operates easily under all conditions and also the sash is protected by the 20 spring arrangement against undue strains, due to weaving of the car body and also the resilient liner protects the sash against transverse strains due to weaving.

What I claim is:

1. In a window construction, the combination 25 with a window opening and sash guide members mounted in the opening; of a sash slideable in the opening along the guide members, each guide member being in the form of a rib, and the sash 30 having a channel for receiving the rib, the channel being offset out of the plane of the sash and parallel thereto, shoes mounted in the channel at spaced apart points along the bottom thereof and coacting with the edge of the rib, and means extending through the bottom of the offset channel and operable to adjust the shoes independently of each other in a direction edgewise of the sash.

2. In a window construction, the combination 40 with a window opening and sash guide members mounted in the opening; of a sash having its stiles provided with portions located out of the plane of and parallel to the sash and slideably interlocking with the guide members, U-shaped 45 resilient cushioning means between the offset portion of the stiles and the guide members, shoes carried by the offset portion and coacting with the guide members, the resilient means being formed with openings in which the shoes are located, an adjusting screw for each shoe extending 50 in a direction edgewise of the offset portion of the stile, the screws having their heads exposed on the outer edges of the offset portions of the stiles.

3. In a window construction, the combination 55 with a window opening, and sash guide members mounted in the opening; of a sash having its stiles slideably coacting with the guide members, each guide member being in the form of a rib, and each stile having a channel offset from the plane 60 of the sash for receiving the rib, a U-shaped resilient liner in the channel between the walls of the channel and the rib, shoes carried at spaced apart points in each channel and coacting with the edge of the rib, the liner being formed with 65 openings in which the shoes are located, means for adjusting the shoes individually in a direction edgewise of the sash including screws threading through the bottom of the channel.

4. In a window construction, the combination 70 with a window opening, and sash guide members mounted in the opening; of a sash having its stiles slideably coacting with the guide members, each guide member being in the form of a rib, and each stile having a channel offset from the 75

plane of the sash for receiving the rib, a U-shaped resilient liner in the channel between the walls of the channel and the rib, shoes carried at spaced apart points in each channel and coacting with the edge of the rib, the liner being formed with openings in which the shoes are located, means

for adjusting the shoes individually in a direction edgewise of the sash including screws threading through the bottom of the channel, and springs interposed between the ends of the screws and the shoes.

ROY T. AXE.
